COMBINATION HOLDER, CARRIER AND DRIP TRAY FOR A VACUUM CLEANER RUG WASHER ATTACHMENT

Ralph A. W. Johanson, Armonk, N.Y., Robert C. Lampe, Stamford, Conn., and Jacques L. Le Baigue, Westbury, N.Y., assignors to Electrolux Corporation, Old Greenwich, Conn., a corporation of Delaware

Filed May 19, 1967, Ser. No. 7,187

Term of patent 14 years

(Cl. D87—1)

FIG. 1

FIG. 2

FIG. 3

FIG. 4

FIG. 5

FIG. 1 is a bottom plan view of a combination holder, carrier and rug washer drip tray for a vacuum cleaner rug washer attachment according to the present invention.

FIG. 2 is a top plan view thereof.

FIG. 3 is a side elevation thereof.

FIG. 4 is a rear elevation thereof.

FIG. 5 is a perspective view thereof.

We claim:

The ornamental design of a combination holder, carrier and drip tray for a vacuum cleaner rug washer attachment, as shown and described.
